(57) **CLAIM**

The ornamental design for a chair, as shown and described.

DESCRIPTION

FIG. 1 is a front elevational view of a chair showing our new design; the portion of the chair illustrated in broken lines shown in an upright position;

FIG. 2 is a back elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a back left perspective view thereof;

FIG. 8 is a front left perspective view thereof;

FIG. 9 is a front elevational view of the chair, the portion of the chair illustrated in broken lines shown in a reclined position;

FIG. 10 is a back elevational view thereof;

FIG. 11 is a right side elevational view thereof;

FIG. 12 is a left side elevational view thereof;

FIG. 13 is a top plan view thereof;

FIG. 14 is a bottom plan view thereof;

FIG. 15 is a back left perspective view thereof; and,

FIG. 16 is front left perspective view thereof.

The broken lines represent the portions of the chair that form no part of the claimed design.
